DECREASING DEIONIZATION OF GAS TUBES

Louis Malter and Edward O. Johnson, Princeton,
N. J., assignors to Radio Corporation of Amer-
ica, a corporation of Delaware

Application April 24, 1951, Serial No. 222,694

18 Claims. (Cl. 315—337)

1

This invention relates to methods of the means for decreasing the de-ionization time of gas tubes and particularly of gas triodes.

As is known, the grid of a gas triode has control for starting ionization of its gaseous filling. For example, if a positive pulse is applied to the negatively biased grid, the tube can be made to fire at a particular instant when its diminishing bias passes from one side to the other of the so-called control characteristic curve. However, once the tube is fired, the grid has substantially no control for interrupting the discharge even if its externally applied bias is made very negative with respect to that curve. Therefore, the grid of an ionized gas triode is said to have "lost control."

The reason for loss of control is that once the gaseous filling is ionized, the negatively biased grid will attract positive ions from the plasma until it is surrounded with enough of them to completely neutralize its bias. Thereafter an increase in the applied bias will merely attract enough additional ions to once more neutralize it. Hence the grid ceases to be effectual as a control electrode. The customary way of restoring the grid to control as a starting electrode is (1) to stop the process of continuous ionization, i. e., to interrupt the discharge, by dropping the anode-cathode potential below the value at which a going arc can be sustained, and (2) to permit deionization ("plasma decay") to take place for a long enough period, by keeping the potential below that value, to allow most of the ions which constitute the grid sheath to recombine with free electrons and diffuse away from the grid. Thus the rate of deionization of its gaseous filling determines the "recovery time" of a thyratron and thereby limits the repetition rate at which it can be cyclically operated as a switch, e. g., in a counter or sweep circuit. This limitation can be clearly understood by considering the behavior of a conventional thyratron in a relaxation-oscillator circuit, e. g., the type of circuit shown in Figs. 5 and 6, which might be used to generate a sweep voltage for an oscilloscope. Assuming the presence of a conventional thyratron as the discharge tube of such a circuit, e. g., connected like the tubes 10 and 10' in Figs. 5 and 6, and assuming that the otherwise readied circuit is first placed in operation by closing a switch (see S in Figs. 5 and 6) in the charging circuit of the storage condenser (see C in these figures), the voltage across this condenser will rise exponentially for a predetermined time to a value near to that required to fire the gas tube

2

at which time a synchronizing voltage will be applied to the control grid to fire the tube. Due to the very low internal resistance of an ionized gas tube the condenser will discharge very rapidly. When it has discharged to below the "extinguishing potential" of the gaseous filling of the tube the plasma will start to decay. However, at the same time that it is decaying the plasma will continue to support conduction and therefore the voltage across the condenser will drop well below the extinguishing potential of the tube and to a value near zero volts. At this point, it is desirable for a fresh cycle to start immediately but if the plasma has not sufficiently decayed, the tube will continue to have a very low impedance, even though it does not fire again, and this will delay the start of recharging. This delay will come to an end when the plasma density has diminished to such a low value that the applied negative bias of the grid is not sufficiently neutralized to prevent it from cutting off the space discharge of the tube for its then small anode potential. Thereafter the effective, i. e., the unneutralized, grid bias and the voltage across the condenser will both progressively increase. However, if the former is too slow with respect to the latter the anode-cathode potential may reach a value to prematurely fire the tube. Where this condition exists, the only solution is to reduce the charging rate. This can be done only at the cost of reducing either the repetition rate of the oscillator, or the peak-to-peak amplitude of the generated saw-tooth voltage, or both. Thus it is seen that the deionization time can limit the repetition rate of a sweep circuit, and/or the rate of change of the sweeping voltage which it generates, and that it can do so both by delaying the start of each charging cycle, and secondly by restricting the rate at which recharging can take place. For this reason, it is very desirable to increase the speed with which deionization takes place in a gas tube.

The advantages which will be obtained by attaining a speeding up of ionization will not be limited to sweep circuits but will extend to a variety of other circuits to which gas tubes are employed, e. g., counters, welder timers, transmitter-tube pulse-modulators.

Accordingly, it is an object of the present invention to decrease the de-ionization time of a gas tube.

It is a further object of this invention to decrease the recovery time of the grid of a gas triode.

In general, this object is obtained according to the present invention through methods of and means for accelerating the plasma decay and therefore the dissipation of the grid ion sheath, by maintaining high electron temperatures within the tube during de-ionization.

In the drawing, Figure 1 is a side view of a gas triode according to the present invention with its envelope partly cut away;

Figure 2 is a transverse sectional view of the triode of Figure 1, the section being taken along the line 2—2 of Figure 1;

Figure 3 is a transverse sectional view of a modification of the triode shown in Figures 1 and 2, the section being taken as in Figure 2;

Figure 4 is a plot of two curves of plasma-density vs. time to show the difference in behavior between gas triodes according to the present invention and conventional gas triodes; and

Figures 5 and 6 are schematic circuit diagrams employing gas triodes as in Figures 1 and 2 and 3 respectively.

The thyratron 10 shown in Figures 1 and 2 comprises a vacuum envelope 11 containing a gas filling represented by the symbol G. Arranged co-axially within the envelope 11 there are in the order named: an indirectly heated cathode 12, a slotted cylindrical control grid 13 having a slot 16, and an anode 14. Since the present invention does not relate to the use of any particular structural features and does not require any particular modification or adaptation of structural features known to the prior art, the showing of tube 10 herein does not include many of the structural details which would be found in an actual physical embodiment, i. e., a heater for the cathode 12, support elements for the various electrodes, their respective leads and terminal pins, a tubulation, etc. However, it is understood that these various necessary parts are to be incorporated into any actual tube embodying this invention and that they may be incorporated in accordance with the teachings of prior art. The portions of the tube 10 comprising its elements 11—14 as taken alone constitute a conventional thyratron. It may be modified in one way according to the present invention by the addition of a tungsten filament 15 in the region between the control grid 13 and the anode 14 either alone or, as shown in Figure 2, in combination with a subsidiary anode 21.

In a series of tests of the deionization rates of conventional gas tubes we discovered that between the firing of a tube employed as an on-off switch and the complete recovery of grid control, the temperature of the free electrons in the plasma rapidly fell from elevated temperatures of about 10,000° K. encountered in the going arc to temperatures in two different ranges: (1) one near the temperature of cathode 12, for electrons inside of the control grid 13, and (2) another near room temperature for the electrons outside of the control grid 13, i. e., between it and the anode 14. Investigation of this phenomenon led to the conclusion that early in the process of plasma decay the grid's sheath of positive ions progressively increases in thickness, to make up for its diminishing density, and does so to such an extent that the portions of the sheath which surround the edges of the slot 16 come together so as effectively to divide the plasma into a first portion within the control grid and a second portion outside thereof. Due to the continued emission of "hot" electrons from the cathode 12 the free electrons of the first portion of the plas-

ma do not cool down below the cathode temperature. This maintains the electron diffusion rate at a high value and, since ions will diffuse at the same rate as electrons, the behaviour known as ambipolar diffusion, the diffusion rate of the relatively massive positive ions in said first portion of the plasma will also be maintained at a high value. As is known this will result in rapid plasma decay. The region outside of the grid, however, is isolated from the cathode's hot electrons. Therefore, the free electrons of the second portion of the plasma quickly cool to room temperature after which ambipolar diffusion and plasma decay proceed relatively slowly.

According to the present invention a means is provided for maintaining high electron temperatures in the portion of the plasma located between the grid and the anode to thereby accelerate the decay thereof. Attained reductions in the recovery time of the grid have been by a factor of the order of 2—3.

The electron heating means shown in Figure 2 comprises an incandescent filament 15 which may be used either alone or in combination with a subsidiary anode 21, or some other electrode for performing its intended (as described below) function. When the filament 15 is used alone it should be connected to a source of heater current but otherwise may be left floating, for example, its end may be connected across an ungrounded battery (see 30 in Figure 5) or to the terminals of the ungrounded secondary of the filament transformer. When so operated the filament 15 may to some extent perform its function of heating free electrons whether it is simply a heater, i. e., a hot wire, or is a copious emitter such as a thoriated tungsten cathode. However, it is far less efficient to use it as a mere heat source rather than as a source of hot electrons. Used as an emitter the thermal velocities of its electrons can easily maintain the average temperature of the plasma electrons at some 2200° K. above room temperature without any substantial measurable increase in the average temperature of the actual structural parts of the tube.

While the filament 15 is shown in a preferred position in alignment with the slot 16, it is not necessary that it be so located. This is possible because of the fact that a continuous plasma tends to have the same average diffusion rate throughout its entire volume and that as a result the electron temperature of the region between the grid 13 and the anode 14 will be substantially uniform regardless of where the filament 15 is placed. From the foregoing it is apparent that while a source of hot electrons is to be preferred over a simple heater as a means for maintaining the free electrons of the plasma at high temperatures nevertheless the latter is within the scope of this invention. Accordingly, it is possible, though not preferred, to use a resistive heater outside the anode, for example, wound about it or even outside of the envelope in which case the entire tube 10 would be heated.

It has been found that an indirectly heated oxide type of cathode may be used as a source of hot electrons instead of the filament 15. However, such cathodes have lower operating temperatures in a region near one thousand degrees K. Therefore a tungsten filament is to be preferred. This illustrates a principle of the invention, that a high average thermal velocity for the hot electrons provided by the heater means is more important than a large number thereof.

Since the electron temperature in a going arc

may be of the order of ten thousand degrees K., it is apparent that an auxiliary discharge can provide electrons of even higher temperature than an incandescent tungsten filament. This can be done in a number of ways such as by using the subsidiary anode 21 in cooperation with the filament 15 or by an embodiment as in Figure 2. Where an auxiliary discharge is set up between the filament 15 and the subsidiary anode 21 to serve as a source of hot electrons its current should be limited to a very small value so that it will not serve as a copious source of plasma. Obviously if the current is not so limited the grid will never recover since its sheath will be continuously replenished by ions from the auxiliary discharge. Accordingly the energizing circuit for the auxiliary discharge comprises, in addition to a source of potential 31, a limiting resistor 32.

Curve A in Figure 4 represents qualitatively the decay of plasma in a conventional gas tube over a period of time starting at the instant when the anode-cathode potential is removed. For this curve it is noted that: (1) the rate of decay is relatively slow; and (2) that the plasma density finally reaches zero. Curve B represents the decay in a tube in which a low-current auxiliary discharge is maintained during the extinguishment of the main discharge. For this curve it is noted that: (1) the rate of decay is greatly increased; and (2) that though the plasma density quickly reaches a low value it never goes to zero. The current of the auxiliary discharge should be so low that the above-mentioned low value of the residual plasma is so low that the grid can recover control despite its presence.

Most of the elements in Figure 3 are of similar construction to corresponding elements in Figure 2 and therefore bear the same reference numerals. However, the anode 14' comprises a foraminous portion 17 which, as will be explained, serves as an electron transparent region through which hot electrons may be admitted into the interelectrode space between the anode and the grid. Outside of the anode 14' and adjacent its foraminous portion 17 there is a box-shaped shield 19 containing a subsidiary cathode 20 and a subsidiary anode 21'.

In the operation of the embodiment of Figure 3 a source of potential sufficient to sustain a going arc between the subsidiary cathode and anode 20, 21' is connected therebetween. The connection should be over a limiting resistor of large value since a small discharge current will suffice for the purposes herein. In fact this will cause the auxiliary discharge to better perform its intended function herein since its small-magnitude current will result in a somewhat higher arc drop and this will result in higher electron temperatures. As shown in Figure 6, the entire circuit comprising the subsidiary cathode and anode of tube 10', the source 31 and the resistor 32 may be left floating. The same is true of the shield 19. The reason for this is that the plasma produced in the auxiliary discharge will be so conductive that it will of its own accord assume a fixed potential relationship with respect to the anode 14'. This will result in satisfactory operation since electrostatic acceleration is not required to move hot electrons from the auxiliary discharge through the foraminous portion 17 into the space between the grid 13 and the anode 14'. It is not required inasmuch as the high thermal velocities of the free electrons of the plasma will suffice to carry many of them through the foraminous portion 17.

When the shield 19 is left floating, it will collect enough charged particles, due to their thermal velocities, to become charged to a point where the velocities of like particles will be opposed by its field and thus it too will automatically assume a fixed potential. However, if desired, either the subsidiary cathode or anode or some part of the circuit which interconnects them may be deliberately polarized so that the plasma will assume a potential near that of the anode 14' or one which is somewhat negative with respect thereto. If the plasma potential is below that of the anode 14', it will establish an electrostatic gradient which will assist the hot electrons in getting through the foraminous portion 17. Likewise the screen 19 may be polarized below the potential of the anode 14' to cause, or to assist in causing, a drift of hot electrons through the portion 17 toward the interior of the anode 14'.

Referring again to the embodiment of Figure 2, it is noted that the type of operation involving the cooperative use of the filament 15 and the subsidiary anode 21 can be obtained in a tube in which no subsidiary anode 21, as such, is provided. For example, this kind of operation can be obtained by causing a small wall area of the main anode 14 which is adjacent to the filament 15 to perform the function of the omitted subsidiary anode 21. In such a case the filament 15 would be polarized at a negative potential with respect to the anode 14 by the use of an energizing circuit like those, already described, which include a limiting resistor 32. Moreover, the same type of operation can be obtained, if preferred, by similarly causing a small area of the outer surface of the control grid 13 to perform the function of the omitted anode 21.

It is apparent from the foregoing that the principle of this invention can be ideally applied to a simple cold cathode gas tube. In such a tube the temperature of all of the free electrons fall to room temperature soon after the anode potential is removed, this being true since there is no hot cathode in the tube at all. In other words, the conditions which cause a slow rate of plasma decay in a restricted portion of a thyratron cause it to be slow throughout a cold cathode tube. Accordingly, any of the free-electron heating-means shown herein may be added to such a tube to hasten its deionization. In the case of a cold cathode which has no grid recovery time problem, since it has no grid, a considerable improvement in performance will nevertheless be obtained because of a reduction in the period during which the tube continues to be conductive though the anode potential has been removed, i. e., the period which, in the above example of a sweep circuit, occurs immediately after the start of the storage condenser discharge. As explained above during this period the decaying plasma effectively short circuits the storage condenser and thereby delays the start of the next charging cycle. Obviously the shortening of this interval will improve the cold cathode gas tube as a switch apart from any additionally attained shortening of grid recovery time.

While the current limiting effect of the resistor 32 can be very effective for preventing the auxiliary discharge from producing too much plasma while acting as a source of hot electrons, it is less effective for increasing the arc-drop. A more effective way of increasing the arc-drop is to operate the subsidiary cathode, 15 or 20 as the case may be, with temperature limited emission. By so doing, both desirable ends will

be attained: (1) The auxiliary current will be kept low, and with it the generation of plasma; and (2) the arc drop will be very substantially increased. The greater arc drop will result in increased electron acceleration(s), i. e., "hotter" electrons. In this connection it may be noted that two distinct ways of provided hot electrons have been described herein. One is by thermionic emission and the other is by thermionic emission plus acceleration. In the case of the latter, some ionization is unavoidable inasmuch as the auxiliary space discharge occurs through the gaseous filling of the tube. However, the ionization per se is a side effect, which, while it serves to increase the magnitude of the auxiliary discharge, does so without increasing the temperatures of the electrons beyond their values due to acceleration over the discharge path. However, as was explained above, the generation of plasma in the auxiliary discharge can be tolerated if it is kept low enough.

What is claimed is:

1. A gas tube comprising: a sealed envelope containing an ionizable medium, a cathode and an anode, and means adjacent to said anode and other than said cathode for heating electrons in the region close to said anode to prevent cooling of said electrons said medium in the absence of a gaseous discharge between the anode and cathode.

2. A gas tube comprising: a sealed envelope containing an ionizable medium and in the order named a cathode, a control electrode and an anode; and means adjacent said anode for heating electrons in the region between said control electrode and anode.

3. A gas switch tube comprising: a sealed envelope containing an ionizable medium and in the order named a cathode, a control electrode and an anode; and means adjacent said anode for heating the electrons in the portion of said medium between said control electrode and anode; said means comprising an electrical heating element in heat exchange relationship with the portion of said medium near the anode.

4. A gas switch tube comprising: a sealed envelope containing an ionizable medium and in the order named a cathode, a control electrode and an anode; and means adjacent said anode for heating the electrons in the portion of said medium between said control electrode and anode; said means comprising a resistive filament between said control electrode and anode.

5. A switch tube as in claim 4 in which said filament is a directly heated thermionic cathode.

6. A gas switch tube comprising: a sealed envelope containing an ionizable medium and in the order named a cathode, a control electrode and an anode; and means adjacent said anode for heating the electrons in the portion of said medium between said control electrode and anode; said means comprising a subsidiary cathode and a subsidiary anode in cooperative spaced relationship for producing an auxiliary gaseous discharge to provide hot electrons to said portion of the medium while generating plasma of very much lower density than that generated between said cathode and anode during current conduction therebetween.

7. A switch tube as in claim 6 in which said subsidiary cathode and anode are located in a region on the far side of said anode from said control electrode and a portion of said anode between said region and said control electrode is electron-transparent.

8. A gas switch tube comprising: a sealed envelope containing an ionizable medium and in the order named a cathode, a control electrode and an anode; and means adjacent said anode for heating the electrons in the portion of said medium between said control electrode and anode; said means comprising a thermionic cathode between said control electrode and anode.

9. A gas switch tube comprising: a sealed envelope containing an ionizable medium and in the order named a cathode, a control electrode and an anode; and means adjacent said anode for heating the electrons in the portion of said medium between said control electrode and anode; said control electrode including a metal plate having a slot in alignment with said cathode and a portion of said anode and said means comprising means for providing hot electrons to said portion of said medium in a region thereof near to said slot.

10. A gas switch tube comprising: a sealed envelope containing an ionizable medium and in the order named a cathode, a control electrode and an anode; and means adjacent said anode for heating the electrons in the portion of said medium between said control electrode and anode; said means comprising a subsidiary temperature limiting cathode and a subsidiary anode in cooperative spaced relationship for producing an auxiliary space discharge.

11. A gas switch tube comprising: a sealed envelope containing an ionizable medium and in the order named a cathode, a control electrode and an anode; and means adjacent said anode for heating the electrons in the portion of said medium between said control electrode and anode; said means comprising a subsidiary temperature limited cathode in cooperative spaced relationship with another electrode within the envelope to produce an auxiliary space discharge.

12. A gas switch tube comprising a sealed envelope containing an ionizable medium, a cold cathode, an anode and means for heating the electrons in medium in the absence of a gaseous discharge between the anode and cathode.

13. A switch tube as in claim 12 in which said means comprises a resistive filament.

14. A switch tube as in claim 13 in which said filament is a directly heated thermionic cathode.

15. A switch tube as in claim 12 in which said means comprises a subsidiary cathode and a subsidiary anode in cooperative spaced relationship for producing an auxiliary discharge to provide hot electrons to said medium without generating sufficient plasma to support an anode to cathode current of gaseous discharge proportions.

16. A switch tube as in claim 15 which further comprises a control electrode between said cathode and anode and in which said means is located adjacent the anode for heating a portion of said medium between said control electrode and anode.

17. A switch tube as in claim 12 in which said means comprises a subsidiary temperature limited cathode and a subsidiary anode in cooperative spaced relationship for producing an auxiliary spaced discharge.

18. Gas tube switching apparatus comprising a sealed envelope containing an ionizable medium, a cathode and an anode, and means other than said cathode for heating electrons in said medium in the absence of a spacious discharge between said anode and cathode; said means comprising a subsidiary cathode for producing an auxiliary discharge to another electrode within the envelope and an auxiliary discharge ener-

gizing circuit connected between the subsidiary cathode and said last-mentioned electrode and including a resistor for so limiting the current of the auxiliary discharge that it cannot generate sufficient plasma to support the anode to cathode current carried by the tube when it is to be actuated as an on-switch.
